UNITED STATES PATENT OFFICE.

EDWARD S. PRESTON, OF CHICAGO, ILLINOIS, ASSIGNOR TO EDMUNDS & JONES CORPORATION, OF DETROIT, MICHIGAN, A CORPORATION OF NEW YORK.

ELECTRIC CIGAR LIGHTER.

Application filed May 26, 1924. Serial No. 715,915.

To all whom it may concern:

Be it known that I, EDWARD S. PRESTON, citizen of the United States, residing at Chicago, in the county of Cook and State 5 of Illinois, have invented certain new and useful Improvements in an Electric Cigar Lighter; and I do hereby declare the following to be a full, clear, and exact description of the invention, such as will enable others 10 skilled in the art to which it appertains to make and use the same.

My invention relates to electric cigar lighters of the general class in which an electrically heated wire is exposed at the 15 mouth of a casing and is heated when the switching member of the appliance is actuated.

Generally speaking, my invention aims to provide a simple, inexpensive, compact and 20 durable appliance of this kind in which the portion carrying the heating wire can readily be removed and replaced without disconnecting the circuit wires from the appliance, and in which the heating wire can 25 easily be replaced even by an amateur. It also provides a cigar lighter of this general class in which the switching member is normally out of engagement with both of the contact elements through which it is 30 adapted to close the circuit and is mounted so as to adjust itself to variations in the relative positions of these contact elements, and in which the switching member is also adapted to be moved during the operation 35 of the device so as to present different portions thereof for engagement with the contact elements.

Furthermore, my invention aims to provide a cigar lighter construction in which 40 both of the circuit wire terminals are carried by one insulator and in which the heating wire is carried by another insulator spaced from the aforesaid insulator; in which a continuously closed circuit connection is made from the heating wire to 45 one of the wire terminals through the metal casing of the lighter and in which screws threaded into the casing and forming part of this circuit connection also serve for holding 50 the two insulators in their normal positions. Moreover, my invention aims to provide a cigar lighter construction in which the switching member is carried by a plunger mounted for movement transversely of the 55 casing of the lighter and in which a simple

spiral spring serves for retracting the plunger. It also provides a novel mounting for the switching member whereby this member is free to tilt or rock to some extent with respect to the plunger so as to afford a good contact with the associated two contact members when the latter are not in exact alinement.

Still further and also more detailed objects will appear from the following specification and from the accompanying drawings, in which—

Fig. 1 is a side elevation of an electric cigar lighter embodying my invention.

Fig. 2 is a front elevation of the same.

Fig. 3 is a central and longitudinal section through the same, taken along the line 3—3 of Fig. 2.

Fig. 4 is an enlarged and fragmentary section taken longitudinally of the casing 75 through the upper portion of the actuating member when the circuit is closed through the latter, showing the switching member as tilted for engagement with two contact elements which are not in exact alinement.

Fig. 5 is a fragmentary section taken centrally and longitudinally of the casing from the line 5—5 of Fig. 2.

Fig. 6 is a perspective view of the rear insulator before it is inserted in the casing, together with the two wire terminals carried by this insulator.

Fig. 7 is a similar perspective view of the forward insulator and the elements mounted thereon.

In the embodiment of the drawings, the cigar lighter of my invention has a metal casing comprising a substantially cylindrical shell 1 having a contracted and perforated rear end 2 and a forwardly flaring mouth. 95 This flaring mouth serves to guide the end of a cigar towards the high resistance heating wire 3 which is disposed in spiral formation in the recess forward end of an insulator 5 and this wire has its inner end 100 portion 4 projecting into the bore of the insulator and clamped within a hollow metal heater terminal 7 by a binding screw 6, which screw also secures the heater terminal in fixed position with respect to the insulator 5. The outer end of the wire 3 is looped through a perforation in a metal clip 8 which is seated in a lateral recess in the insulator 5, this clip being forced towards 105 the insulator and into clamping relation to 110

- the said outer end of the heating wire by a screw 9 threaded into the wall 1 of the casing.
- The heater terminal 7 projects rearwardly of the casing beyond the insulator 5 towards a wire terminal 11 which is partly housed by another insulator 10 also mounted within the cylindrical shell 1 and projecting forwardly beyond that insulator, but the two terminals 7 and 11 are spaced from each other by a considerable distance to permit a spring and spring guide to extend between them out of contact with both. The wire terminal 11 desirably has its rear end bored out for receiving the tip of a circuit wire 12 so that this can be clamped to the bore of the wire terminal by a screw 13 which has its head fitting a transverse bore in the insulator 10 so as to anchor the wire terminal 11 to this rear insulator. The rear insulator 10 also has a lateral recess, desirably in alignment with that in the forward insulator 5, and this recess houses a metal eye 14 through which the end of the companion circuit wire 22 is looped, after which this eye is forced towards the insulator 10 and into clamping relation to the said wire loop by a screw 15 threaded into the shell of the casing.
- This shell 1 is provided at a point between the two insulators with two perforations disposed diametrically opposite each other. Threaded into one of these perforations is a screw 16 which has its main stem portion unthreaded and extending towards and desirably into the opposite perforation as shown in Fig. 4, this latter perforation being considerably larger in diameter than the said stem. Slidably mounted on this stem is a push member 17 which normally projects for a considerable distance beyond the casing and which has an insulating washer 19 secured to its inner end. This insulating washer has a channel-sectional metal ring 20 spun around it, the ring having a bore so much greater than that of the inner end of the push member 17 so that the insulator will keep the ring out of contact with the push member. However, the ring preferably is spun only loosely over the insulator, so that it can rock with respect to the latter. Moreover, the switching member (as thus constituted by the push member 17, the insulator 19 and the ring-shaped contact member 20) is continuously urged towards the adjacent side of the metal shell by a spiral spring 18 interposed between the inner end of the push member and the threaded portion of the screw 16.
- With the parts thus arranged, it will be obvious from the drawings that the screws 9 and 15 cooperate with the metal shell of the casing to afford a continuous circuit connection from the wire 22 to the outer end of the heater wire, while the connec-

tion between the inner end of this heater wire and the companion circuit wire 12 is normally interrupted by the gap between the heater terminal 7 and the wire terminal 11. When the push member 17 is pressed inwardly of the casing against the resistance of the spring, the metal contact member 20 is forced into engagement with the adjacent end portions of the terminals 7 and 11, thereby closing the circuit as long as the button is pressed inwardly. By mounting the ring-shaped contact member 20 loosely on the washer 19, I permit this contact member to rock as shown in Fig. 4, thereby enabling it to afford a good circuit connection even though the two terminals are not aligned with each other.

Furthermore, since the push head 17 is freely rotatable on the stem 4, the ordinary and often careless pushing and pressing action of the user's thumb on this push member will gradually rotate the latter and rotate the contact member with it, thereby causing the latter to present fresh portions in engagement with the terminals 7 and 11. Consequently, my simple arrangement insures clean and firm contacts, while the use of a spiral compression spring enables me to avoid the changes which commonly occur in flat springs and particularly when these are also used for carrying the current after the manner heretofore employed in electric cigar lighter constructions. By anchoring the insulating washer 19 to the push member 17, I can employ the wall of the casing as a stop for limiting the outward movement of the switching member, so that no auxiliary element is needed for this purpose, and by arranging the screws 9 and 15 as above described, I cause these to serve the further purposes of holding the two insulators in their normal positions.

Should the heating wire be damaged or burn out at any time, the forward insulator and the parts carried by the latter can instantly be withdrawn after merely removing the screw 9 without disconnecting the circuit wires or the switching means from the casing. Consequently, a renewal of the heating wire can be made very quickly even by the ordinary user.

In practice, I desirably slip an insulating washer 24 into the space between the contracted rear end 2 of the casing and the rear insulator, so as to receive the thrust from the usual knot in the circuit wires, thereby preventing any undue pulling strain on these wires from loosening the connections to the wires. However, I do not wish to be limited to these or other details of the construction and arrangement here disclosed, it being obvious that the same might be modified in many ways without departing either from the spirit of my invention or from the appended claims.

I claim as my invention:

1. A cigar lighter comprising a frontal heating wire, a rearwardly extending heater terminal connected to one end of the heating wire, a wire terminal spaced from the heater terminal, a circuit connection to the other end of the heating wire, a plunger yieldingly mounted for movement transversely of the said terminals, and a contact member carried by the plunger and adapted to engage both terminals. 75

2. A cigar lighter comprising a frontal heating wire, a rearwardly extending heater terminal connected to one end of the heating wire, a wire terminal spaced from the heater terminal, a circuit connection to the other end of the heating wire, a plunger yieldingly mounted for movement transversely of the said terminals, and a contact member carried by the plunger and adapted to engage both terminals, the contact member being mounted to permit tilting thereof with respect to the plunger. 80

3. A cigar lighter comprising a frontal heating wire, a rearwardly extending heater terminal connected to one end of the heating wire, a wire terminal spaced from the heater terminal, a circuit connection to the other end of the heating wire, a plunger yieldingly mounted for movement transversely of the said terminals, an insulator fast on the plunger, and a contact member so mounted on the insulator as to permit a rocking thereof on the insulator. 85

4. A cigar lighter comprising a frontal heating wire, a rearwardly extending heater terminal connected to one end of the heating wire, a wire terminal spaced from the heater terminal, a circuit connection to the other end of the heating wire, a plunger yieldingly mounted for movement transversely of the said terminals, and a contact member carried by the plunger and adapted to engage both terminals, the contact member comprising an insulator fast upon the plunger and a metal ring loosely spun over the edge of the insulator. 90

5. An electric cigar lighter comprising a forwardly open casing, a heater terminal and a wire terminal both mounted within the casing and having relatively adjacent portions spaced from each other, a heating wire connected at one end to the heater terminal, circuit connections leading respectively to the other end of the heater terminal and to the wire terminal, a contact member mounted for movement towards and away from the said adjacent terminal portions and adapted to engage both of the said portions simultaneously, and spring means normally holding the contact member out of such engagement. 95

6. An electric cigar lighter comprising a forwardly open casing, a heater terminal and a wire terminal both mounted within the casing and having relatively adjacent portions spaced from each other, a heating wire connected at one end to the heater terminal, circuit connections leading respectively to the other end of the heater terminal and to the wire terminal, a guide member extending transversely of the casing, a contact carrier slidably mounted on the guide member for movement towards and away from the said adjacent terminal portions, a contact member carried by the carrier adapted to engage both of the said portions simultaneously, and spring means normally retracting the contact carrier to hold the contact member out of such engagement. 100

7. An electric cigar lighter comprising a forwardly open casing, a heater terminal and a wire terminal both mounted within the casing and having relatively adjacent portions spaced from each other, a heating wire connected at one end to the heater terminal, circuit connections leading respectively to the other end of the heater terminal and to the wire terminal, a guide member extending transversely of the casing, a contact carrier slidably mounted on the guide member for movement towards and away from the said adjacent terminal portions, a contact member carried by the carrier adapted to engage both of the said portions simultaneously, and spring means normally retracting the contact carrier to hold the contact member out of such engagement. 105

8. An electric cigar lighter comprising a forwardly open casing, a heater terminal and a wire terminal both mounted within the casing and having relatively adjacent portions spaced from each other, a heating wire connected at one end to the heater terminal, circuit connections leading respectively to the other end of the heater terminal and to the wire terminal, a guide member extending transversely of the casing, a contact carrier slidably mounted on the guide member for movement towards and away from the said adjacent terminal portions, a contact member carried by the carrier adapted to engage both of the said portions simultaneously, and spring means normally retracting the contact carrier to hold the contact member out of such engagement, the contact carrier having a portion projecting through the casing. 110

9. An electric cigar lighter comprising a forwardly open casing, a heater terminal and a wire terminal both mounted within the casing and having relatively adjacent portions spaced from each other, a heating wire connected at one end to the heater terminal, circuit connections leading respectively to the other end of the heater terminal and to the wire terminal, a guide member extending transversely of the casing, a contact carrier slidably mounted on the guide member for movement towards and away from the said adjacent terminal portions, a contact member carried by the carrier adapted to engage both of the said portions simultaneously, and spring means normally holding the contact member out of such engagement. 115

10. A cigar lighter comprising a frontal heating wire, a rearwardly extending heater terminal connected to one end of the heating wire, a wire terminal spaced from the heater terminal, a circuit connection to the other end of the heating wire, a plunger yieldingly mounted for movement transversely of the said terminals, and a contact member carried by the plunger and adapted to engage both terminals. 120

11. A cigar lighter comprising a frontal heating wire, a rearwardly extending heater terminal connected to one end of the heating wire, a wire terminal spaced from the heater terminal, a circuit connection to the other end of the heating wire, a plunger yieldingly mounted for movement transversely of the said terminals, and a contact member carried by the plunger and adapted to engage both terminals, the contact member being mounted to permit tilting thereof with respect to the plunger. 125

12. A cigar lighter comprising a frontal heating wire, a rearwardly extending heater terminal connected to one end of the heating wire, a wire terminal spaced from the heater terminal, a circuit connection to the other end of the heating wire, a plunger yieldingly mounted for movement transversely of the said terminals, an insulator fast on the plunger, and a contact member so mounted on the insulator as to permit a rocking thereof on the insulator. 130

away from the said adjacent terminal portions, a contact member carried by the carrier adapted to engage both of the said portions simultaneously, and spring means normally retracting the contact carrier to hold the contact member out of such engagement, the casing having an aperture in one side and the contact carrier having a portion normally projecting through the aperture, 5 in combination with a guide stem supported by the other side of the casing and upon which the contact carrier is slidably mounted.

10. A cigar lighter comprising a heating wire, a heater terminal connected to one end thereof, a wire terminal supported in spaced relation to the heater terminal, a source of current having one pole connected to the wire terminal and the other pole connected to the other end of the heater terminal, an actuating member slidably mounted for movement towards and away from the said two terminals, a metal contact member rockingly mounted on the actuating 20 member and adapted to engage both of the said terminals when moved in one direction, and spring means continuously urging the actuating member in the opposite direction.

11. An electric cigar lighter comprising a metal casing, a pair of insulators mounted therein and spaced longitudinally of the casing, a heater terminal and a wire terminal respectively mounted on the forward and rear insulators and projecting towards 30 each other, a heating wire carried by the forward insulator and having its ends respectively connected to the heater terminal and the casing, a metal switching member movable transversely of the casing and 35 adapted to contact with both of the said terminals, and yielding means normally holding the switching member out of contact with both terminals.

12. An electric cigar lighter comprising a metal casing, a pair of insulators mounted therein and spaced longitudinally of the casing, a heater terminal and a wire terminal respectively mounted on the forward and rear insulators and projecting towards 40 each other, a heating wire carried by the forward insulator and having one end connected to the heater terminal, a conducting

member carried by the forward insulator and connected to the other end of the heating wire, a second conducting member carried by the rear insulator, a movable switching member operable from outside the casing for electrically connecting the heater terminal with the wire terminal, and means electrically connecting both of the conducting 55 members with the metal casing.

13. An electric cigar lighter comprising a metal casing, a pair of insulators mounted therein and spaced longitudinally of the casing, a heater terminal and a wire terminal respectively mounted on the forward and rear insulators and projecting towards each other, a heating wire carried by the forward insulator and having one end connected to the heater terminal, a conducting member carried by the forward insulator and connected to the other end of the heating wire, a second conducting member carried by the rear insulator, a movable switching member operable from outside the casing for electrically connecting the heater terminal with the wire terminal, and a pair of screws respectively electrically connecting the two conducting members with the metal casing.

14. An electric cigar lighter comprising a metal casing, a pair of insulators mounted therein and spaced longitudinally of the casing, a heater terminal and a wire terminal respectively mounted on the forward and rear insulators and projecting towards each other, a heating wire carried by the forward insulator and having one end connected to the heater terminal, a conducting member carried by the forward insulator and connected to the other end of the heating wire, a second conducting member carried by the rear insulator, a movable switching member operable from outside the casing for electrically connecting the heater terminal with the wire terminal, and a pair of screws respectively electrically connecting the two conducting members with the metal casing, the screws serving also to anchor the insulators in their respective 80 positions in the casing.

Signed at Chicago, Illinois, May 23rd, 1924.

EDWARD S. PRESTON.
